US00D798957S

(12) **United States Design Patent** (10) **Patent No.:** **US D798,957 S**
(45) **Date of Patent:** **** Oct. 3, 2017**

(54) **INTERACTIVE GAME PIECE**

(71) Applicant: **STICHTING PREVENTIEVE MERKENBESCHERMING, Amsterdam (NL)**

(72) Inventor: **Maxwell Charles Griffin Ford, London (GB)**

(**) Term: **15 Years**

(21) Appl. No.: **35/500,039**

(22) Filed: **Jun. 12, 2015**

(80) **Hague Agreement Data**

Int. Filing Date: **Jun. 12, 2015**

Int. Reg. No.: **DM/086820**

Int. Reg. Date: **Jun. 12, 2015**

Int. Reg. Pub. Date: **Jul. 10, 2015**

(51) **LOC (10) CI.** **21-01**

(52) **U.S. Cl.**

USPC **D21/385**

(58) **Field of Classification Search**

USPC D21/478-480, 385, 386, 396, 397

See application file for complete search history.

Primary Examiner — Barbara Fox

(57) **CLAIM**

The ornamental design for an interactive game piece in the shape of a card, as shown and described.

DESCRIPTION

Figure 1.1 is a front view of an interactive game piece showing the new design.

Figure 1.2 is a perspective view thereof.

Figure 1.3 is a front view thereof, shown in a condition of use.

Figure 1.4 is a perspective view thereof.

The broken lines showing a human form in Figures 1.3 and 1.4 illustrate environment and form no part of the claimed design.
